(57) **CLAIM**

The ornamental design for a solar powered lamp, as shown and described.

DESCRIPTION

FIG. 1 is a front view of a solar powered lamp, in a first embodiment;

FIG. 2 is a left-side view thereof—the right-side view thereof is identical;

FIG. 3 is a top perspective view of a solar powered lamp which shows photovoltaic element at the top;

FIG. 4 is an aerial view thereof;

FIG. 5 is a front view of a solar powered lamp, in a second embodiment;

FIG. 6 is a left-side view thereof—the right-side view thereof is identical;

FIG. 7 is a top perspective view of a solar powered lamp which shows the photovoltaic element at the top;

FIG. 8 is an aerial view thereof;

FIG. 9 is a front view of a solar powered lamp, in a third embodiment;

FIG. 10 is a left-side view thereof—the right-side view thereof is identical;

FIG. 11 is a top perspective view of a solar powered lamp which shows the photovoltaic element at the top;

FIG. 12 is an aerial view thereof;

FIG. 13 is a front view of a solar powered lamp, in a fourth embodiment;

FIG. 14 is a left-side view thereof—the right-side view thereof is identical;

FIG. 15 is a top perspective view of a solar powered lamp which shows the photovoltaic element at the top; and,

FIG. 16 is an aerial view thereof.
